MANUAL DATA ENTRY SLIDER ASSEMBLY CONSOLE

Loring C. Bixler, Endicott, and Robert K. Hayes and
Louis H. Sedaris, Endwell, N.Y., assignors to Interna-
tional Business Machines Corporation, New York,
N.Y., a corporation of New York

Filed Dec. 14, 1960, Ser. No. 63,226

Term of patent 14 years

(Cl. D26—5)

FIG. 1

FIG. 2

FIG. 3

FIG. 6

FIG. 4

FIG. 5

FIG. 1 is a front perspective view of a manual data entry slider assembly console showing our new design. FIGURE 2 is a top perspective view of the same. FIG. 3 is a rear elevational view of the same.

FIG. 4 is a left side elevational view of the same.

FIG. 5 is a right side elevational view of the same.

FIG. 6 is a large scale fragmentary view of a pair of slider dials with one in a depressed or actuated position.

We claim:

The ornamental design for a manual data entry slider assembly console, as shown.
